UNITED STATES PATENT OFFICE.

JOHN DAVIS, OF ALLEGHENY, PENNSYLVANIA.

FILTER.

SPECIFICATION forming part of Letters Patent No. 402,656, dated May 7, 1889.

Application filed July 30, 1887. Serial No. 245,716. (No model.)

To all whom it may concern:

Be it known that I, JOHN DAVIS, a citizen of the United States, residing at Allegheny, in the county of Allegheny and State of Pennsylvania, have invented certain new and useful Improvements in Filters; and I do hereby declare the following to be a full, clear, and exact description of the invention, such as will enable others skilled in the art to which it appertains to make and use the same.

This invention relates to filters, and has for its object certain improvements on the filter shown in my application for a patent, Serial No. 220,215, as will be hereinafter described, and particularly pointed out in the claims.

In the accompanying drawings, which form a part of this specification, Figure 1 represents a vertical section on line $y-y$ of Fig. 2. Fig. 2 is a plan view of the receiving-chamber with the supply-pipe shown in section. Fig. 3 is an enlarged vertical section, showing the valve for controlling the supply of chemicals. Fig. 4 is an enlarged plan view, partly in section, showing the ejector in the circulating-pipe. Fig. 5 is a vertical section of the valve controlling the supply of water to the filter-bed. Fig. 6 is an inverted plan view of the same; Fig. 7, a vertical section of a modified construction. Fig. 8 is a plan of a battery of filters connected and a sand-washing vessel in section, and Fig. 9 is a plan of a modified construction of the bottom for the filtering material to rest upon.

Reference being had to the drawings and the letters marked thereon, A represents the filter as a whole, which is formed in two detachable sections, B C, and a base, D, secured together by rods a in any suitable or required number. The upper section, B, is designed to contain sand or other suitable filtering material, and is provided with a removable top, b , a bottom, c , and an interposed bottom or diaphragm, d , of fine-mesh wire, upon which the body of sand rests. The wire bottom, d , is supported upon suitable metallic bars, e , and between it and the bottom c is the supply-pipe f to the filter-chamber for washing the filter-bed and the discharge-pipe g , both of which have their ends protected by wire-gauze caps h . The discharge-pipe g extends to the upper end of the filter-chamber, where it is provided with an opening, j , also protected by wire-

gauze for the escape of dirty water when the filter-bed is being washed, as will hereinafter more fully appear.

The discharge of the filtered and the dirty water, which passes through the filter-bed in filtering and cleansing the filter, is controlled by a three-way cock, k .

The pipe g may be led through section B at any point below that shown. For supplying water for filtering through the filter-bed a pipe, l , extends up through the filter-chamber and terminates in a gauze-protected end, m , and discharges water above the surface of the filter-bed. (Not shown.) The water for supplying the filter-chamber, whether for filtering purposes or for washing the filter-bed, is controlled by a valve, n , having two ports, o p , for registering with the pipes f and l , and is operated by a rod, q , which projects through the cover b of section B. The construction of the valve n is clearly shown in the enlarged views in Figs. 5 and 6. The filter-chamber is also provided with an agitator, E, the shaft r of which rests upon and projects through the bottom c of the filter-chamber, and extends through and secures the diaphragm s in position by means of the nut t , while the opposite end of the shaft projects through the top, b , of the section B, in which there is a stuffing-box, as shown in Fig. 7, and is surmounted by a crank-lever, u , for agitating the filter-bed when it is being cleansed.

The diaphragm s is composed of a perforated piece of sheet metal, v , and a sheet of asbestos cloth, w , secured to the under side thereof, and is forced up between the periphery of the disk v and the annular inclined wall x of the section B, making a water-tight joint, where it is secured by the nut, t , on the end of the shaft, r , of the agitator, and forms a chamber, y' , between it and the bottom, c , of the filter-chamber, for containing strained water to be supplied to the filter-chamber either for filtering or washing the filter-bed. The lower or asbestos-cloth side of the diaphragm s is cleaned or the accumulated sediment removed by a rod, z , in the nut t by the movement of the agitator.

In small filters—such as for household use—the filter-bed may be cleansed by agitation and forcing water upward through it under

the pressure of the city or town water system; but for large filters—such as for supplying cities, towns, or manufactories—the filter-bed can be more thoroughly cleansed by transferring 5 the sand or filtering material from one filter-chamber to another, or into a washer, from which it is again transferred to the filter. To accomplish this, I provide a pipe, a' , which may be of any suitable flexible material, and 10 which extends near the bottom of the filter-chamber, and is supported by an arm, b' , attached to the shaft r of the agitator, and is controlled by a valve, c' . When the filter-bed is to be transferred 15 from one filter-chamber into another, or into a separate washer, the water for cleansing and raising the filter-bed is admitted at the bottom of the filter-chamber through pipe f , instead of on top of the bed through pipe l , 20 when, by agitation of the bed and the force of the water, the bed is raised and transferred from one filter into another, or into a separate washer by the side of the filter, the dirty water being permitted to flow off through 25 a suitable valve—such as passage j' and valve k —or through a valve, (not shown,) which may be connected lower down with the outlet-pipe g . While the filter-bed is being transferred the flexible pipe a' is moved or swung about the 30 filter-chamber by the oscillations of the agitator E and the arm b' , and thereby assumes different positions in the arc of a circle and collects the filtering material at different points in the chamber. 35 The lower section, C , of the filter is provided with a flange, d' , and a seat, e' , having a packing-ring, f' , upon which the lower end of the section B rests and forms a watertight joint, and within said section is a ret- 40 ceiving-chamber, g' , a sediment-chamber, h' , a chemical-chamber, i' , and a circulating-pipe, k' , all of which are fully described in my application, Serial No. 220,215. The water from the receiving-chamber enters the chemical-chamber through an aperture, l' , and the 45 chemicals are delivered into the circulating-pipe k' through a pipe, m' , which is provided with a valve, n' , to regulate the quantity of chemical solution supplied. The valve 50 n' consists of a body, o' , which is provided with a conical seat, p' , and two ports or passages, $q' r'$, in different vertical planes, a screw-threaded conical plug, s' , and an operating-disk, t' . 55 Upon the outer surface of the disk t' is secured a circular leaf-spring, u' , which supports a stud or pin, v' , which projects through the disk t' and enters apertures w' in the outer end of the body o' . By this construction 60 the valve may be set to graduate the flow of chemicals to any desired amount without danger of the valve moving and changing the flow.

To set the valve, the pin v' is withdrawn 65 from the aperture w' , in which it is seated, the plug s' screwed back from its seat until the pin registers with another aperture, when

the spring u' will automatically force the pin into said aperture and lock the valve. The chemicals are raised by the combined action 70 of three forces: first, by the pressure of the column of water in the receiving-chamber; second, by the velocity of the column of water in the circulating-pipe; and, third, by the vacuum formed by an ejector in the circulat- 75 ing-pipe.

By reference to Figs. 2 and 4 it will be observed that the supply-pipe a'' and the valve b'' are of greater cross-sectional area than the circulating-pipe k' , and as a consequence the 80 velocity of the column of water is increased, and in the circulating-pipe is formed an ejector, c'' , of any approved form, by which a partial vacuum is formed in the circulating-pipe. Fig. 2 also shows the outlet of the branch 85 d'' of the supply-pipe of greater cross-sectional area than the area of the circulating-pipe k' , for the purpose of admitting water to the filter in greater quantity for cleansing purposes. 90

All the water which enters the receiving-chamber, whether for filtering or cleansing purposes, passes through the asbestos cloth w , where it is deprived of all its coarser impurities and only the finer particles of impure 95 matter pass up into the filter-bed, where they are arrested.

By removing the major portion of the impurities from the water used for cleansing the filter-bed it can be effected more rapidly and 100 thoroughly than can be done by the use of water containing all of its impurities. The sediment is withdrawn from the chamber h' through an opening, e'' , and a suitable stop-cock, and the chemicals, whether in solid or 105 liquid form, are supplied to the chamber i' through an opening, f'' , provided with a removable cover, g'' .

In the application of my filtering system to water-supplies to cities or towns the filters are 110 grouped together, as shown in Fig. 8, and each filter is provided with a suitable water supply and discharge pipe, a sediment-discharge pipe, and all of the filters are connected by transfer-pipes h'' , for transferring the filter-bed from one filter to another in succession 115 throughout the system for cleansing it; or a washer, F , may be provided and connected to each of the filters by a pipe, i'' , by which the filter-bed may be transferred to the washer as 120 a means of cleansing it by the attrition of the filtering material on itself, and then returned to the filter from which it came by means in the washer similar to those in the filter, whereby it was transferred into the washer. 125

In Figs. 1 and 9 I have shown the bottom d made of a coil of wire, instead of woven wire, as in Fig. 7. In this construction the wire is from one-eighth to one-fourth of an inch in diameter, is closely coiled and supported upon 130 metallic bars e , as in the other construction, and forms a more durable bottom than the woven wire.

In my application, Serial No. 291,377, I have

claimed a coagulating and precipitating chamber, a chemical-chamber, and suitable connections for supplying and charging water with chemicals and for discharging purified water.

Having thus fully described my invention, what I claim is—

1. In a filter, the combination of a supply-pipe, a receiving and precipitating chamber, a filter-chamber, an interposed straining-diaphragm, a chamber between the diaphragm and the bottom of the filter-bed, pipes communicating with the chamber above the diaphragm, the filter-chamber above and below the filter-bed, and an agitator, substantially as described.
2. In a filter, the combination of a supply-pipe, a receiving and precipitating chamber, a filter-chamber, an interposed straining-diaphragm, a chamber between the filter-bed and the bottom of the filter-chamber, pipes communicating with the intermediate chamber and discharging above and below the filter-bed, a pipe for drawing off liquid above and below said bed, valves for controlling each of said pipes, and an agitator, substantially as described.
3. In a filter, the combination of a supply-pipe having a valve and provided with distributing-branches, a receiving and precipitating chamber, a chamber for containing chemicals, a circulating-pipe of smaller area

than the supply-pipe and communicating with the chemical-chamber and one of said branches, a filter-chamber, a chamber between the receiving-chamber and the filter-bed, pipes for supplying and drawing liquid from the filter-chamber, and an agitator, substantially as described.

4. A filter composed of an upper and a lower detachable section, the lower section being provided with a receiving and a precipitating chamber, a chemical-chamber, and a circulating-pipe communicating with the chemical-chamber, the upper section having a filter-chamber provided with a foraminous diaphragm supporting the filter-bed, a supply-pipe extending above the filter-bed, an inlet and a discharge pipe under said diaphragm, and a waste-water discharge above the filter-bed, in combination with an agitator, substantially as described.

5. In a filter, the combination of a filter-chamber, a water-supply pipe, an agitator, and a flexible transfer-pipe connected to an arm on the agitator, substantially as described.

In testimony whereof I affix my signature in presence of two witnesses.

JOHN DAVIS.
